UNITED STATES PATENT OFFICE.

CHARLES H. WILLSON, OF MEDFORD, ASSIGNOR TO JAMES W. BROOKS, OF PETERSHAM, AND FRANK F. STANLEY, OF SWAMPSCOTT, MASSACHUSETTS, TRUSTEES.

DESIGN FOR A NAIL OR SLUG.

SPECIFICATION forming part of Design No. 25,087, dated January 21, 1896.

Application filed December 18, 1895. Serial No. 572,610. Term of patent 3½ years.

To all whom it may concern:

Be it known that I, CHARLES H. WILLSON, of Medford, county of Middlesex, and State of Massachusetts, have invented and produced 5 a certain new and useful Design for a Nail or Slug, of which the following is a specification, reference being had to the accompanying drawings, forming a part thereof.

Figure 1 of the drawings is an isometric 10 view of a nail or slug, illustrating my design; and Fig. 2 is an end view thereof.

The leading feature of my design consists in a nail or slug having one longitudinal edge rounded to form a cylindrical portion and its 15 other edge curved to form a portion elliptical in cross-section, said portions being connected by a triangular prism, the base of which rests upon the elliptical portion.

In the drawings the triangular prismatic portion *a* is shown with its apex intersecting 20 a cylindrical portion *b*, forming one longitudinal edge of the nail or slug, the base of the prism *a* being connected to portion *c* elliptical in cross-section, forming the other longitudinal edge of the nail or slug. 25

I claim—

The design for a nail or slug, substantially as set forth.

In testimony whereof I have signed my name to this specification in the presence of 30 two subscribing witnesses.

CHARLES H. WILLSON.

Witnesses:

JOHN C. EDWARDS,
FREDERICK L. EMERY.
